UNITED STATES PATENT OFFICE.

JOHN H. SCHEU, OF NEW YORK, N. Y.

INKING MECHANISM FOR PRINTING-PRESSES.

1,114,188.

Specification of Letters Patent. Patented Oct. 20, 1914.

Application filed August 5, 1913. Serial No. 783,032.

To all whom it may concern:

Be it known that I, JOHN H. SCHEU, a citizen of the United States, and residing at New York, in the county of New York and State of New York, have invented certain new and useful Improvements in Inking Mechanism for Printing-PresSES, of which the following is a specification, such as will enable those skilled in the art to which it appertains to make and use the same.

This invention relates to printing presses, and particularly to what are known as job printing presses, and in its practical application, the invention relates particularly to inking mechanism for presses of this class; and the object thereof is to provide a press of this class having a flat rectangular inking table and the usual table inking rollers which operate in connection with said table, and by means of which the ink is applied to said table with my improved inking mechanism, whereby, the printing in parallel rows of different colors may be produced at one operation; and with this and other objects in view the invention consists in an inking mechanism for purposes of the class specified, constructed and operating as herein-after described and claimed.

The invention is fully disclosed in the following specification of which the accompanying drawings form a part, in which the separate parts of my improvement are designated by suitable reference characters in each of the views, and in which;

Figure 1 is a plan view of a part of a job printing press provided with my improvement;—Fig. 2 a side view thereof;—Fig. 3 a longitudinal vertical section on the line 3—3 of Fig. 1;—Fig. 4 a transverse vertical section on the line 4—4 of Fig. 3, and;—Fig. 5 a similar section on the line 5—5 of Fig. 3.

In the accompanying drawings I have shown only such parts as are necessary to illustrate my invention, the printing form or form rollers or platen and the form inking roller or rollers by which the ink is taken from the inking table and applied to the form roller or platen being now shown.

In said drawings I have shown at *a* the inking table, and at *b*, *c* and *d* parts of the

frame which support the usual inking mechanism in the printing parts of this machine, said parts consisting, in the construction shown, of upright members, and I have 55 also shown at *e* another part of said frame with which the table *a* is connected.

Mounted in the top of the part *c* of the frame is a main inking roller *f*, and in the top of the part *d* is a supplemental main 60 inking roller *g*, and the inking roller *f* consists of a central shaft *f*² which is angular in cross section and on which is mounted a plurality of inking disks *f*³ which are three in number, in the construction shown, 65 and these inking rollers are spaced by means of collars or sleeves *f*⁴. The supplemental main inking roller *g* also comprises a central shaft *g*² angular in cross section and on which are mounted a plurality of inking 70 disks *g*³ which, in the construction shown, are three in number, and these inking disks are also spaced by collars or sleeves *g*⁴, and in the use of my improvement, the distance between the inking disks *f*³ and the inking 75 disks *g*³ may be increased or decreased by employing longer or shorter spacing collars or sleeves, as will be readily understood.

The shaft *f*² of the main inking roller *f* is provided at one end with a projecting 80 trunnion *f*⁵ on which is mounted a gear *f*⁶, and on which is also mounted a cam disk *f*⁷ provided with a peripheral groove *f*⁸, and mounted above and at the back of the main inking roller *f* are ink spreading rollers *h* 85 and *h*² mounted on shafts *h*³ and *h*⁴ provided at one end with trunnions *h*⁵ and *h*⁶, and these trunnions are provided with pins *h*⁷ and *h*⁸ which move in the groove *f*⁸ of the cam disk *f*⁷, and by means of this construction the ink spreading rollers *h* and *h*², in the operation of the machine, are given a longitudinal oscillating or vibratory movement, this result being effected by reason of the fact that the rollers *h* and *h*² are rotatably mounted on the shafts *h*³ and *h*⁴ and also move longitudinally with said shaft, and this result may be accomplished by providing the shafts *h*³ and *h*⁴ with stop pins *h*⁹ at the ends of the rollers *h* and *h*². 95

Mounted in front of the supplemental main ink roller *g* are two ink spreading

rollers i and i^2 which correspond with the ink spreading rollers h and h^2 and which are constructed and operated in the same manner as said rollers h and h^2 , the supplemental main ink roller g , or the shaft g^2 thereof being provided at one end with a trunnion g^5 on which is mounted a gear g^6 and a cam disk g^7 provided with a peripheral groove g^8 , and the ink spreading rollers 10 i and i^2 are mounted on shafts i^3 and i^4 having end trunnions i^5 and i^6 provided with pins i^7 and i^8 which operate in the groove g^8 of the cam disk g^7 , and by means of this construction the ink spreading rollers i and 15 i^2 are also given a longitudinal oscillating and vibratory movement, together with a rotary movement, said movements being the same as that of the ink spreading rollers h and h^2 .

20 Mounted rearwardly of the main ink roller f are font rollers j and j^2 , and the font roller j operates in the usual manner in the fountain j^3 , while the font roller j^2 has a forward and backward movement and takes the ink 25 from the roller j and applies it to the disks f^3 on the main ink roller f , this construction being old and well known. Beneath the main ink roller f are other font rollers k and k^2 , and the font roller k operates in the usual 30 manner in the font k^3 , and the roller k^2 has a forward and backward movement and takes the ink from the roller k and applies it to the disk g^3 of the roller g .

In the accompanying drawings I have 35 shown at m and m^2 the table inking rollers which are mounted in the usual manner in the carriage m^3 and movable forwardly and backwardly over the table a , and said carriage is provided at both sides with link members m^4 which connect with corresponding link members m^5 , and in practice, the link members m^5 are connected with the form inking rollers, not shown, and by which the ink is applied to the printing form or 40 platen, also not shown. The rollers m and m^2 are vertically movable in the carriage m^3 , but the construction and operation of the parts m , m^2 , m^3 , m^4 and m^5 being the same as in other machines of this class.

45 The table a is provided with the usual backwardly directed arms n , and directly over the supplemental main ink roller g these arms are provided with raised tracks n^2 , and in the operation of the machine the carriage m^3 and rollers m mounted thereon, move back and forth over the arms n as well as over the table a , and in Fig. 3 of the accompanying drawings, the rollers m and the carriage m^3 are shown in their rearmost 50 position in full lines, and in their foremost position in dotted lines. In the above described operation, the roller m rides up over the tracks or ways n^2 and does not come in contact with the supplement inking roller g , but does come in contact with the main

inking roller f . This result being accomplished by means of small track rollers m^6 mounted on the trunnions of the roller m and which ride over the tracks or ways n^2 .

The table inking rollers m each apply one 70 color to the table a , and as shown, the front roller m^2 applies blue ink and the roller m , red, and in Fig. 1 of the drawings, I have indicated blue ink at x and red ink at x^2 , and it will be understood from Fig. 3 of the 75 drawings, that the roller f applies the red ink to the roller m , and the roller g the blue ink to the roller m^2 .

80 Mounted in the part c of the frame is the usual drive shaft o provided with a pinion o^2 which meshes with the gears f^6 and g^6 on the trunnions f^5 and g^5 of the shafts f^2 and g^2 , and by means of this construction the rollers f and g are given a rotary movement. The parts c and d of the frame are each 85 provided at one side thereof with detachable members c^2 and d^2 which permit of the adjusting of the disks f^3 and g^3 on the shafts f^2 and g^2 , or the insertion or the interchanging 90 of disks of various widths which will be determined by the operator.

In the operation of this machine, the rollers f and g are given a rotary movement, the table inking rollers m and m^2 are moved forwardly and backwardly over said table, 95 and said rollers and the fountain rollers j^2 and k^2 are moved forwardly and backwardly, all this being accomplished by the usual operation of the machine, but with my construction instead of applying one color of 100 ink to the table a , I apply different colors in parallel lines, and although I have shown the colors applied to the table in lines of the same width, it will be understood that the width of each of these lines and the number 105 of said lines will be determined by the disks f^3 and g^3 , as hereinbefore described.

110 My invention is not limited to any exact construction for the table ink applying rollers m and m^2 , and these rollers may be constructed in the same manner as the rollers f and g , if desired, and changes in and modifications of the other features of construction herein shown and described may be made, within the scope of the appended 115 claim, without departing from the spirit of my invention or sacrificing its advantages.

Having fully described my invention what I claim as new and desire to secure by Letters Patent is:—

120 A printing press having two main inking rollers each of which is provided with a plurality of spaced inking disks, an inking table in front of said rollers and provided with tracks or ways which extend backwardly thereover, a carriage movable over said table and over said tracks or ways and provided with two ink applying rollers adapted to operate in connection with the main inking rollers and to apply ink to said table, and 125 130

means whereby when the carriage moves backwardly over the inking rollers, one of the ink applying rollers in said carriage will be raised above the front of the main inking

5 rollers.

In testimony that I claim the foregoing as my invention I have signed my name in

presence of the subscribing witnesses this 2nd day of August 1913.

JOHN H. SCHEU.
